UNITED STATES PATENT OFFICE.

DANIEL S. WAUGH, OF DENVER, COLORADO, ASSIGNOR TO THE DENVER ROCK DRILL AND MACHINERY CO., OF DENVER, COLORADO.

DRILL-HOLE-CLEANING ATTACHMENT FOR HAMMER-DRILLS.

1,023,899.

Specification of Letters Patent. Patented Apr. 23, 1912.

Application filed May 26, 1908, Serial No. 435,113. Renewed July 14, 1909. Serial No. 507,584.

To all whom it may concern:

Be it known that I, DANIEL S. WAUGH, a citizen of the United States, residing in the city and county of Denver and State of Colorado, have invented certain new and useful Improvements in Drill-Hole-Cleaning Attachments for Hammer-Drills; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in means for controlling the passage of air and water to the drill hole in hammer drills.

By virtue of my improvement, the same valve that regulates the supply of water to the drill hole, may also be utilized for cutting off the water and turning on the air whereby the one or the other fluid as may be desired may be utilized for this purpose. In putting in down-holes it is preferred to utilize the water, while in drilling up-holes, it is preferred to utilize the air since in the up-hole work the drill cuttings are washed out in the form of mud and interfere with the work of those in charge of the drill. On the other hand it is advisable to use the water as much as possible since it obviates or overcomes the dust incident to the use of air alone for cleaning the drill hole.

By virtue of my improvement the mechanism may be readily adjusted to cut off the water and turn on the air or vice versa without stopping the machine. To this end I employ a three way valve adapted to be so adjusted that one of its ports communicates with a passage leading from the motive fluid supply of the main valve, at the same time cutting off the water supply. Again the valve may be so adjusted as to cut off the air supply and allow the passage of water to the drill hole.

Having briefly outlined my improved construction, I will proceed to describe the same in detail reference being made to the accompanying drawing in which is illustrated an embodiment thereof.

In this drawing, Figure 1 is an elevation illustrating a hammer drill equipped with my improvements, the drill steel and a portion of the body of the drill being shown in

section. Fig. 2 is a section taken through the valve mechanism, the parts being shown on a larger scale. This section is taken on the line 2—2 Fig. 3. Fig. 3 is a similar section taken at right angles to Fig. 2. This section may be said to be taken on the line 3—3 Fig. 2. Figs. 4, 5 and 6 are gross sections taken on the lines 4—4, 5—5 and 6—6 respectively, of Fig. 2. Fig. 7 is a perspective view in detail illustrating the valve for controlling the supply of fluid (air or water) to the passage communicating with the opening through the drill steel.

The same reference characters indicate the same parts in all the views.

Let the numeral 5 designate the body of the drill and 6 the valve for controlling the motive fluid supply thereto. Threaded into a reinforced part 7 of the casing, is a valve casing 8 in which is located a valve piece 9. Connected with this casing 8 is a motive fluid supply conduit 10 which communicates with a motive fluid chamber 12 formed in the casing 8. This chamber is in communication with a chamber 13 of the main valve. From the chamber 13 a passage 14 leads to a chamber 15 from which a passage 16 leads to the drill for the purpose of operating the hammer. As the movement of the hammer has nothing to do with this application further description of the general drill mechanism will not be required.

The valve piece 9 has an opening 17 leading downwardly from its upper or larger extremity, this opening being in communication with the chamber 12 and which the motive fluid entering through the conduit 10 is adapted to enter. This opening 17 communicates with a short lateral passage 18 formed in the valve and opening upon its outer surface whereby the opening 17 is in communication with a lateral opening 19 formed in the valve casing and communicating with a passage 20, the latter being in communication with a short passage 21 leading to a main passage 22 which extends through the wall of the drill casing and communicates at its forward extremity with a chamber 23 surrounding the rear extremity of the drill steel 24 and in communication with an angular passage 25 formed in a tappet 26 which engages the rear extremity of the drill steel and is acted on by the hammer (not shown). The passage 25 is in communication with the ion-

itudinal passage 27 extending through the drill steel. Hence if it is desired to employ the motive fluid as air for drill hole cleaning purposes, the valve 9 is adjusted 5 to bring its opening 17 into communication with the passages 20, 21 and 22.

For the purpose of introducing water to the drill hole, a water pipe 28 is connected with the drill casing and communicates 10 with a passage 29 formed in the valve piece 9, when the latter is properly adjusted or when the valve piece is in the position indicated in Figs. 4 and 5. The passage 29 in the valve piece extends to the 15 center thereof and communicates with a passage 30 which when the valve is adjusted as shown in Figs. 4 and 5 is in communication with the passage 20, whereby water entering the valve through the conduit 28 flows through the various passages 20 which are in communication with the passage 27 of the drill steel.

A coil spring 31 is located in the chamber 12 and its opposite extremities engage 25 the valve pieces 6 and 9 respectively.

For the purpose of imparting a partial rotary movement in reverse directions to the drill body and drill steel, a handle 32 is provided. This handle has a threaded 30 reduced portion 33 screwed into a threaded opening formed in the outer extremity of the valve casing 8 in alinement with the valve piece 9. A sleeve 34 engages the body 35 of the handle 32 at one extremity and the outer portion of the valve casing 8 at its opposite extremity. This sleeve is loosely mounted upon the said parts whereby it may be rotated thereon for the purpose of actuating the valve 9 whereby the passages 40 of the valve through which the air and water pass, may be brought into communication with the passages leading to the drill steel as may be required. This sleeve is connected with the valve piece 9 by means 45 of a screw 35 which is threaded into the valve piece and passes through a slot 36 formed in the casing 8 and extending one-fourth the distance around the said casing. The head of the screw enters a slot 37 50 formed in the inner extremity of the sleeve 34, whereby the sleeve and screw are interlocked. Hence as the sleeve is given a quarter turn in the one direction or the other, the valve piece 9 is given a corresponding movement, whereby its passage 17 55 or its passage 29 and 30, may be brought into communication with the passage 20 as may be required. This sleeve may be readily actuated for the purpose of adjusting the valve piece, since the handle 32 is normally grasped by the operator for the purpose of rotating the drill. Now whenever it is desired to change the position of the valve piece, it is only necessary for the 60 operator to move his hand inwardly a short

distance, in order to grasp the sleeve and impart thereto the necessary movement. This act may be performed without interfering in any way with the rotary movement of the drill. In other words the valve 70 piece 9 may be adjusted for the purpose of introducing either air or water for the purpose of changing from one to the other, without interrupting the operation of the drill.

From the foregoing description the use 75 and operation of my improved attachment will be readily understood.

Assuming that it is desired to introduce water to the drill hole, the valve piece 9 is adjusted as shown in the drawing whereby the water conduit 28 is in communication with the angular passage 29, 30, the latter being in communication with the passage 20 through which the water flows to the passage 22 and thence through the drill steel and into the 85 drill hole as heretofore explained. Now if it is desired to introduce air or motive fluid to the drill hole, the operator grasps the sleeve 34 which is loosely mounted upon the handle and casing 8 as heretofore explained, 90 and gives the latter a quarter turn, whereby the passage 17, 18 in the valve piece is brought into communication with the water conduit 28 being simultaneously cut off.

It will be understood that the valve piece 9 95 is manipulated independently of the main valve 6, whereby the passage of fluid either air or water to the drill hole may be accomplished without interfering in any way with the passage of motive fluid to the drill for 100 the purpose of reciprocating the hammer. In other words the motive fluid conduit 10 is in communication with the chamber 12 at all times, the latter being in communication with the various passages leading to the 105 hammer chamber as heretofore explained.

Having thus described my invention, what I claim is:

1. In a drill hole cleaning attachment for motive fluid actuated drills, the combination 110 with the drill body, and means for supplying motive fluid thereto, of a valve casing connected with the drill body through which the motive fluid passes to the body of the drill, said drill body and valve casing being 115 provided with a main passage leading from the valve chamber to the drill steel, a valve mounted in said casing, a water conduit connected with the casing, the valve being adjustable and provided with two openings, 120 either of which may be brought into communication with the main passage, whereby when the valve is moved into one position, the motive fluid passes therethrough to the drill steel, while when the valve is moved 125 into the other position the water flows through said passage, substantially as described.

2. The combination with a motive fluid-actuated drill and a motive fluid supply, 130

of a valve chamber mounted on the valve body and in communication with the motive fluid supply, the valve casing and drill body being also provided with a main passage 5 connecting the valve chamber with the drill steel, a water supply in communication with the valve chamber, the valve being provided with two openings for allowing water or motive fluid to flow therethrough to the 10 main passage, a handle for rotating the drill body, the same being connected with the valve casing, a sleeve loosely-mounted on the handle and connected in operative relation with the valve whereby the latter may be 15 manipulated for the purpose of allowing either motive fluid or water to flow through the main passage to the drill steel as may be desired, substantially as described.

3. In mechanism of the character set forth, 20 the combination with drilling mechanism including a motor and a drill bit, of a handle for turning the drilling mechanism having an internal motive fluid chamber communicating with the drilling mechanism 25 and with the drill bit, a motive fluid con-

ducting pipe connected to the chamber, and separate rotary valves controlling the out-flow from the chamber to the motor and drill bit and having substantially coincident axes of rotation.

4. In mechanism of the character set forth, the combination with drilling mechanism, including a motor and a drill bit, of a handle projecting from one side of the drilling mechanism for turning the same, means 30 for delivering fluid to the motor and to the drill bit, a controlling valve for the fluid to the motor having a handle projecting from the side of the drilling mechanism that is opposite the turning handle, and a 35 valve for controlling the supply of fluid to the drill bit mounted in the handle and rotatable on an axis that is disposed longitudinally of the handle.

In testimony whereof I affix my signature 40 in presence of two witnesses.

DANIEL S. WAUGH.
